[57] CLAIM

The ornamental design for a dental flossing tool, substantially as shown and described.

DESCRIPTION

FIG. 1 is a side elevational view of a dental flossing tool showing our new design;

FIG. 2 is a top plan view of the dental flossing tool of FIG. 1;

FIG. 3 is a bottom plan view of the dental flossing tool of FIG. 1;

FIG. 4 is a side elevational view of the dental flossing tool of FIG. 1 as viewed from the opposite side as depicted in FIG. 1;

FIG. 5 is a front elevational view of the dental flossing tool of FIG. 1; and

FIG. 6 is a rear elevational view of the dental flossing tool of FIG. 1.
